METHOD OF MAKING FOOTBALLS

William J. Voit, Los Angeles, and Leith C. Weimer,
Southgate, Calif.; said Weimer assignor to said
Voit

Application September 3, 1940, Serial No. 355,176

7 Claims. (Cl. 154—16)

This invention relates to a method of making footballs and other hollow inflatable athletic play balls.

The walls of athletic play balls of this type are usually built up of a number of layers, each layer being adapted to fulfill a distinctive purpose. An innermost layer is adapted to receive and retain the air of inflation. An outermost layer is adapted to resist wear and abrasion caused by contact of the ball with external objects, and an intermediate layer or layers are adapted to provide additional material to resist puncture and to strengthen the ball against enlargement in diameter under the pressure of inflation. All of the several layers by their composition and in their relationship to each other are adapted to give the ball the requisite play qualities as to resiliency and in other respects.

A layer of wound stranded material, such as fibrous thread or cord, has been found to be effective to serve as an intermediate reinforcing layer between the air retaining innermost layer and the outermost protective covering layer. Sometimes this stranded material is wound upon the ball in great circles, or near great circles, the crossing points of the circles being scattered and rather generally distributed over the surface of the ball. In other cases the stranded material is spirally wound about an axis of the ball as a center, the winding beginning at or adjacent one pole of this axis and terminating at the other pole thereof. In the manufacture of footballs, a spiral winding of this character is about the long axis of the football, it being obviously impractical to wind stranded material in elliptical convolutions lengthwise of the ball.

In winding the stranded material upon the ball, it should be laid on the surface of the ball at a constant tension. This tension depends upon the character of the stranded material and the degree of rigidity which it is desired to impart to the completed article, but whatever the degree of this tension obviously it should be uniform throughout the winding operation so that the wall of the ball may have uniformity of quality throughout its entire extent.

Accordingly, the winding mechanism is designed to feed the stranded material at a uniform tension to the ball. But unless the wall of the ball to which the stranded material is being fed is substantially rigid, it will be temporarily depressed and furrowed by the stranded material at the point of winding contact with the result that the wound ball will be misshapen and will

present undulations interfering with the proper performance of the ball when placed in use.

It has been the practice to attain the desired rigidity of the wall of the ball upon which the stranded material is wound, by building the ball upon a form of solid material. This form is later removed through an opening in the ball which must be left in the layer or envelope of wound, stranded material as well as in any layers of the ball beneath the winding. Either provision is made for lacing this opening, or the opening is permanently closed at later stages of manufacture of the ball. The method of employing a rigid form to ensure even winding of the stranded material upon the ball obviously presents several difficulties, and the resultant product has disadvantages no matter which method of closing the opening for the form is used.

It is one object of this invention to provide 20 rigidity in the foundation wall upon which stranded material is to be wound, in a manner which shall obviate the difficulties and disadvantages attendant upon the use of a solid removable form.

It is another object to afford a rapid inexpensive and simple method of winding at even tension a stranded material upon a ball core or foundation.

It is another object to provide a method of 30 manufacturing a ball which will produce a ball which will not lose its original shape or size, which will be durable, and which will have the requisite play characteristics.

The invention is herein described in connection 35 with the manufacture of a football. In some respects the invention is applicable to the manufacture of hollow, inflatable athletic footballs of other than the ellipsoidal shape of the standard football.

In the drawing:

Fig. 1 is a vertical, sectional view of a bladder disposed within a curing mold.

Fig. 2 is an elevational view illustrating the manner in which a reinforcing wall is applied to the bladder.

Fig. 3 is a vertical section taken along the line 3—3 of Fig. 2.

Fig. 4 is an elevational view illustrating the manner in which stranded material is next wound upon the ball.

Fig. 5 shows the completed ball with a wear-resisting cover applied thereto.

The first step in the manufacture of the football is the making of the air-retaining innermost layer of the ball, commonly called the "bladder."

This may be made in any suitable manner, but preferably pieces of relatively thin sheeted rubber or other rubber-like material are secured together along their marginal edges in the shape of a football to form an air-retaining bladder 11. An inflation valve 12 of a suitable character is secured in place in the bladder 11, preferably at a place midway of the ends 13 and 14 of the bladder. The bladder is then placed in a mold 15 provided with air-conveying means 16, by which air may be forced into the interior of the bladder 11 through the valve 12. The bladder is then inflated and while under inflation is subjected to a heat cure, which hardens the rubber material of the bladder and gives it the definite form of a standard football.

Air pressure in the bladder is removed; the bladder is taken from the mold and reinflated to a size somewhat less than that desired for the completed football. Pieces 17 of woven fabric, which may be rubberized, are then adhesively applied to the inflated bladder preferably with lapped marginal joints. These pieces may be of any number and configuration, but it has been found satisfactory to cover the entire surface of the bladder with at least four similarly shaped and equally dimensioned pieces 17, each extending from the end 13 to the end 14 of the football. In applying the pieces 17 to the bladder, the bladder may be initially dipped in latex or similar material, or rubber cement may be applied to the under surface of the pieces 17 before application to the bladder.

The fabric covered bladder is next placed in a mold of slightly larger dimensions than the mold 15, but otherwise similar thereto. In this mold the ball is inflated by air at a relatively high pressure, for example 90 to 100 pounds, which forces the wall of the ball into intimate contact with the inner surface of the mold, stretching the fabric material of the pieces 17. While thus inflated and while the pieces 17 are in stretched condition, the ball is given a heat-cure, which fixes it in shape and size.

The ball is now deflated sufficiently for removal from the mold and again inflated to a relatively high pressure. When thus inflated it presents at all points a hard unyielding surface, which can only be dented by the application of a very heavy inward thrusting stress. The ball is now placed in a winding machine and thread or cord, or other stranded material 18 is spirally wound upon it, beginning at a point 19 near the pole 13 of the ball and terminating at a point 20 near the other end or pole 14 of the ball. This cord is preferably rubberized.

End caps 21 and 22, consisting of small concavo-convex pieces of rubber or rubberized fabric, are adhesively applied to the ball at its respective ends 13 and 14. These polar caps have substantially the same thickness as the diameter of the stranded material 18 if the latter is wound upon the ball in a single ply, or as the total thickness of the layer of cord windings, if there is more than one ply of windings.

The cord wound ball may now be given a heat-cure in a mold and afterward provided with a wear-resisting cover, or it may be provided with the cover without an intermediate molding cure. The wear-resisting cover may be a one-piece rubber envelope 23 formed by vulcanizing in place upon the ball a plurality of pieces of rubber, or the ball may be mounted within a mold and in spaced relationship with the internal surface of the mold and a liquid rubber material for

the cover flowed into the space between the ball and the mold, and vulcanizing uniting to the ball in the usual manner.

The mold for this last vulcanization may be formed with impressions to cast in the surface of the rubber cover of the ball any desired markings such as simulations 24 of the lacing of a leather ball, these markings facilitating the handling of the ball by the players as well as improving the appearance of the ball.

Or, a leather cover may be given the ball by adhesively applying to the cord-wound carcass a plurality of leather panels, and thereafter preferably giving the leather covered ball a pressure treatment in a mold preferably at a low temperature.

The process is subject to a number of variations without departing from the spirit of the invention. While, as described above, the ball is given a vulcanizing cure after each application of material thereto, one or more of these vulcanizing steps may be omitted from the process, provided that when the ball is completed the rubber material of all of its parts has been properly cured. It is to be preferred, however, that the bladder be at least partially cured before the application of the pieces of fabric, and it is also preferable that the fabric covered ball be enlarged somewhat by internal air pressure and that the rubber material of the fabric be cured while the fibers thereof are in their stretched condition. The word "rubber" as herein used is meant to include not only natural rubber but synthetic materials having the resilient character of rubber such as materials classed as "synthetic rubber."

We claim as our invention:

1. A method of making an athletic ball, comprising: making a valved air-retaining bladder of rubber-like material; inflating said bladder to a relatively low pressure and to a size slightly smaller than that of the completed ball; bonding to said inflated bladder an envelope of fabric woven material highly resistant to tensile stresses; inflating said enveloped bladder without substantial enlargement to a substantially higher pressure sufficient to substantially resist the inwardly directed stresses applied thereto during the operation of winding at a substantial tension a reinforcing layer of stranded material thereon; winding stranded material at a substantial tension on and bonding it to said inflated bladder to form a reinforcing layer; and applying and bonding a wear-resisting cover to said ball.

2. A method of making an athletic ball, comprising: making a valved air-retaining bladder of rubber-like material; inflating said bladder to a relatively low pressure and to a size slightly smaller than that of the completed ball; bonding to said inflated bladder an envelope of fabric woven material highly resistant to tensile stresses; inflating said enveloped bladder without substantial enlargement to a substantially higher pressure sufficient to substantially resist the inwardly directed stresses applied thereto during the operation of winding at a substantial tension a reinforcing layer of stranded material thereon; spirally winding stranded material at a substantial tension on and bonding it to said inflated enveloped bladder between opposite poles to form a reinforcing layer; and applying and bonding a wear-resisting cover to said ball.

3. A method of making an ellipsoidal football, comprising: making a relatively thin walled in-

latable bladder of cured rubber material having an inflation valve, and in the shape of the completed article; inflating said bladder to a relatively low pressure and to a size slightly smaller than that of the completed ball; applying thereto with a vulcanizable rubber adhesive an envelope of longitudinally tapering, marginally secured pieces of fabric material highly resistant to tensile stresses; inflating said fabric covered bladder without substantial enlargement to a 10 substantially higher pressure sufficient to render it locally substantially unyieldable inwardly when subjected to the stresses arising from winding thereon stranded material at a substantial feed tension adequate for properly forming a reinforcing envelope of stranded material; spirally winding stranded material on the inflated fabric covered bladder at a substantial tension and about the long axis of the bladder; applying a wear-resisting covering envelope to the ball; and giving the ball a vulcanizing cure in a mold.

4. A method of making an ellipsoidal football, comprising: making a relatively thin walled inflatable bladder of cured rubber material having an inflation valve, and in the shape of the completed article; inflating said bladder to a relatively low pressure and to a size slightly smaller than that of the completed ball; applying thereto with a vulcanizable rubber adhesive an envelope of marginally secured, lune-shaped pieces of rubberized fabric material highly resistant to tensile stresses; inflating said fabric covered bladder without substantial enlargement to a substantially higher pressure sufficient to render it locally substantially unyieldable inwardly when subjected to the stresses arising from winding thereon stranded material at a substantial feed tension adequate for properly forming a reinforcing envelope of stranded material; spirally winding on the inflated fabric covered bladder rubberized stranded material at a substantial tension and about the long axis of the bladder; curing the ball in a mold; and applying a wear-resisting cover to the ball.

5. A method of making an ellipsoidal football, comprising: making a relatively thin walled inflatable ball of cured rubber material having an inflation valve, and in the shape of the completed article; inflating said ball to a relatively low pressure and to a size slightly smaller than that of the completed ball; applying thereto with a vulcanizable rubber adhesive an envelope of marginally secured, lune-shaped pieces of rubberized fabric material highly resistant to tensile stresses; inflating said fabric covered ball without substantial enlargement to a substantially higher pressure sufficient to render it locally substantially unyieldable inwardly when

subjected to the stresses arising from winding thereon stranded material at a substantial feed tension adequate for properly forming a reinforcing envelope of stranded material; spirally winding on the inflated fabric covered ball rubberized stranded material at substantial tension and about the long axis of the ball; applying a wear-resisting, rubber cover to the ball; and giving the ball a vulcanizing cure in a mold.

6. A method of making an ellipsoidal football, comprising: making a relatively thin walled inflatable bladder of rubber material having an inflation valve, and in the shape of the completed article; inflating said bladder to a relatively low pressure and to a size slightly smaller than that of the completed ball; applying thereto, with a vulcanizable rubber adhesive, an envelope of marginally secured pieces of rubberized fabric material highly resistant to tensile stresses; vulcanizing said envelope and bladder; inflating said fabric covered bladder without substantial enlargement to a substantially higher pressure sufficient to render it locally substantially unyieldable inwardly when subjected to the stresses arising from winding thereon stranded material at a substantial feed tension adequate for properly forming a reinforcing envelope of stranded material; spirally winding on the inflated fabric covered bladder rubberized stranded material at a substantial tension and about the long axis of the bladder; curing the ball in a mold; and applying a wear-resisting cover to the ball.

7. A method of making an ellipsoidal football, comprising: making a relatively thin walled inflatable bladder of rubber material having an inflation valve, and in the shape of the completed article; inflating said bladder to a relatively low pressure and to a size slightly smaller than that of the completed ball; applying thereto by means of vulcanizable rubber adhesive and with marginally lapped joints, pieces of fabric material highly resistant to tensile stresses to form an envelope; inflating said fabric covered bladder without substantial enlargement to a substantially higher pressure sufficient to render it locally substantially unyieldable inwardly when subjected to the stresses arising from winding thereon stranded material at a substantial feed tension adequate for properly forming a reinforcing envelope of stranded material; spirally winding stranded material on the inflated fabric covered bladder at a substantial tension and about the long axis of the bladder; applying a wear-resisting covering envelope to the ball; and giving the ball a vulcanizing cure in a mold.
